UNITED STATES PATENT OFFICE.

FRANK L. FELTES, OF CLEVELAND, OHIO, ASSIGNOR, BY MESNE ASSIGNMENTS, TO ALUMINUM COMPANY OF AMERICA, OF PITTSBURGH, PENNSYLVANIA, A CORPORATION OF PENNSYLVANIA.

PISTON-CASTING MACHINE.

Application filed November 30, 1925. Serial No. 72,276.

This invention relates to casting machines and particularly to that class of such devices utilized in casting or molding pistons and the like.

5 The main object of the invention is to provide a machine with a plurality of cooperating mold and core parts forming a piston or like cavity and arranging, connecting and operating such parts in a manner such that 10 an operator may readily assemble such parts to produce a cavity and core and thereafter remove such parts to release the cast or molded piston or other article.

15 The various features of the invention will be brought out in conjunction with the specific embodiment set forth in the drawings, specification and claims.

20 Referring to the drawings, Fig. 1 is a front elevation of the machine; Fig. 2 is a side elevation; Fig. 3 is a section upon the line 3—3 of Fig. 1, looking in the direction of the arrows indicated on that figure; Fig. 4 is a section upon the line 4—4 of Fig. 1, looking in the direction of the arrows indicated in Fig. 1; Fig. 5 is a top plan view of the main bed of the machine; Fig. 6 is an enlarged vertical sectional view through the main bed when the parts are assembled; Fig. 7 is a section upon the line 7—7 of Fig. 6, 25 looking in the direction of the arrows; Fig. 8 is an enlarged vertical sectional view showing the parts of the mold assembled; Fig. 9 is a section upon the line 9—9 of Fig. 8; Fig. 10 is a detailed section upon the line 30 10—10 of Fig. 8; and Fig. 11 is a detailed section upon the line 11—11, indicated in Fig. 5.

35 In the arrangement shown, 1 represents a main frame provided with a cross member 2 having bearings 3 therein and supporting a shaft 4 having an upstanding handle 5. The upper end of the frame is provided with suitable guides 6 along the front and back for a purpose to be described. The frame 40 is also provided with transverse guide members 7 forming vertical corner guides for an open plunger 8 which is adapted to move up and down in said corner guides. This hollow plunger has a flat upper surface 9 interrupted at the center by a recess which provides a central centering boss for the piston, as will appear. This upper surface 45 is the base or bottom of the mold. As

stated, this plunger is open but is closed at the bottom by a plate 10 provided with a 55 downwardly extending shank 11 adapted to engage an eccentric 12 upon the shaft 4. Slidable laterally above the transverse guide members 7 and in the guide 6 are main mold slides 13, each of which carries a half mold 14 adapted when in assembled position to stand above the hollow plunger 9, as shown in Fig. 8. Each half mold portion 14, when used for molding pistons, is provided, when necessary, with an opening 15 adapted to receive a wrist pin bearing die or mold 16 termed an insert. Each of the mold portions 14 is further provided with a flange 17, the left flange 17 being provided with a pair of ears 18 receiving a pin 19 upon which is pivoted the top plate 20 provided with a centrally disposed core receiving opening 21 for the core and arranged in alignment with the mold cavity, as will appear, and with a projection 22 overlying the 75 right hand flange 17, as shown in Fig. 8. This projection 22 is provided with a shaft 23 having a handle 24 at its upper end and a lower eccentric bevelled edge latch 25 adapted to engage a suitable keeper or hook 80 26 projecting upwardly from the right hand flange 17. By this arrangement when the two halves of the mold are assembled, as shown in Fig. 8, and top plate is in place, the latch may be tightened to draw the top 85 and the two halves of the mold all together and hold them in that position during the casting operation.

90 Each half mold portion or part is provided with a forwardly and upwardly extending portion 14' each of which is provided with a half sprue channel 14'' leading to the cavity and a half riser channel 14'''.

95 Each of the bearing dies or inserts 16 is here shown as rectangular in shape so that it fits a suitably shaped opening 15 and the wall of the opening either of the die, or the part 14, is provided with suitable minute openings or passages 27, Fig. 8, for permitting the discharge of gas from the mold. The inner end of each end of the die is provided with the proper configuration to give the desired shape to the wrist pin bearing and the supports which extend to the walls of the piston. The outer end of each die 100 105 may be provided with suitable flanges 28

adapted to be secured to the outside of the corresponding half mold portion 14 by suitable screws 29. Each die block or insert is further provided with a centrally disposed 5 circular opening 30 for the reception of a wrist pin bearing opening core pin or rod 31. These pins 31 move with the bearing dies and with the half mold portions, as will appear.

- 10 The core rods 31 must be changed from time to time as the machine is used to prevent over heating and this is accomplished by mounting these rods in a turret 32 provided with a shank 33 extending through a 15 vertical bearing 34 in a transverse slide 35 slidable laterally in the guide 6. Each shank 33 is provided with a suitable threaded end 36 for receiving a nut 37. Each turret may also be provided with a 20 handle or knob 38 for rotating the same to bring a new pin in position. In order to position the turret, the main body 32 is provided below the rods with four recesses 39, one for each rod, and these recesses are engaged by a projection 40 on a swinging latch 25 lever 41 pivoted at 42 and having a hook 43 at its opposite end engaged by a spring 44. The recesses 39 and projection 40 are tapered or inclined so that the turret may be 30 ratcheted around to bring a new pin in position to engage in the opening 30.

The half molds 14 and their slides 13 together with the slide 35, carrying the turrets, are moved into and out of casting or molding 35 position in a predetermined sequence and this is accomplished by providing the slides 13 of the half molds with rods 45 projecting from the end of each slide and provided with check nuts 46 adapted to be engaged by a 40 downwardly extending lug 47 carried by the corresponding turret slide 35. Each turret slide is provided with a pair of ears 48 connected by links 49 to levers 50 pivoted intermediate their ends in the frame. These 45 levers have their lower arms connected by links 51, in the case of the right hand levers 50, to upwardly extending crank arms 52 mounted upon the shaft 4, while the left hand levers are connected by links 53 to 50 downwardly extending crank arms 54 also secured to the shaft 4. By this arrangement it will be seen that when the shaft 4 is operated in the proper direction the turret slides and turrets will be moved to bring their 55 rods into the openings 30 of the half molds and continued movement of the shaft 4 will pick up the half mold slides and the half molds and move all of these parts into assembled position over the hollow plunger 8. 60 In the meantime the eccentric 12 raises the hollow plunger 8 up to a position where it engages the bottoms of the two half molds, thus completing the main mold assembly. In order to hold the half molds in this position, the latching mechanism already de-

scribed is operated and the parts are locked in position.

The foregoing description has disposed of the main mold or cavity and it now remains to take up the main central core. 70

Extending upwardly from the main frame 1 is an upper frame 55 having a plurality of guide ways 56 preferably above the mold cavity formed by the mold parts already described. These guide ways receive a plurality of slide rods 57, five in number. The two outer slide rods 57 each carry an inwardly extending arm 58 provided with an outside core part 59 adapted to form a small peripheral portion of the main central core 80 for that portion of the skirt of the piston just below the wrist pin bearing parts. These outside core portions can therefore move up and down freely above the wrist pin bearing dies. Each of these outside 85 core portions 59 is preferably flat on its inside surface 60 and is engaged by the intermediate core portions to be described. The next pair of guide rods 57 are for these intermediate core portions and each rod is 90 pivotally connected to a lateral extension 61 in the form of a lever of the first kind, one arm of the lever being provided with an operating handle 62 and the other arm being provided with a downwardly extending intermediate core member or part 63. Each 95 intermediate core member or part has a slightly inclined transverse face 64 and at its lower end is provided with a laterally extending projection 65 for forming the various configuration necessary for the inside 100 of the top of the piston just above the wrist pin bearing part. Each of these intermediate core members is further provided with an indentation, indicated at 66, for forming the inner part of the wrist pin bearings. In assembling these intermediate core members or parts in the cavity already formed, it is necessary that the lower projecting portions 65 swing laterally to pass the overhanging corresponding pin 31 and 105 wrist pin bearing parts so that the lever mounting 61 at the top permits this swing 110 movement and the arrangement is such that these two intermediate members are lowered in succession, as will be described, the left one moving down first. The operator moves the handle 62, if necessary, to cause the swinging movement so that this 115 particular intermediate core member passes its obstructing parts and passes to final position in the mold. Thereafter upon the descent of the right hand intermediate core member the operator swings this one in the 120 proper manner to pass its pin 31 and other parts. By reason of the incline or taper of the inner surfaces of these two intermediate core members, a V-shaped opening is formed 125 between them and it is engaged by the central or main core member 67 which is wedge 130

shaped and completes the peripheral configuration of the inside of the piston. This main core is mounted on the remaining central slide rod 57.

5 The proper progressive movement of the core members of this main or central core is accomplished by a plurality of properly shaped cams illustrated in Figs. 2, 3 and 4.

The cam 68 in Fig. 2 is provided with a 10 portion 69 for receiving a roller 70 upon a lever 71 pivoted at 72 in the frame and connected by a link 73 to the outside of right hand slide rod 57 for the right hand outside core member or part. The inclination 15 of the cam groove 69 is such that upon the rotation of the cam the parts are actuated and the right hand outside core member or part is moved downward. The groove 69 merges into a concentric groove 74 so that 20 when this concentric portion of the groove reaches the center of gravity no further downward movement of this core member or part results. This cam and all the others to be described, are mounted upon a shaft 25 75 supported in suitable bearings upon the frame.

The next adjacent intermediate core member 63 is actuated by a similar train of mechanism and similar cam and these cams may 30 be set upon the shaft so that these parts move together or the intermediate core member or part may follow the right hand outside core member or part. The left hand outside and intermediate core members are 35 operated by similar mechanism employing a cam of the type shown in Fig. 4, consisting of the main body portion 76 mounted upon the shaft 75 and having a concentric groove 77 which delays the downward movement 40 of these two core members until the right hand pair previously described have reached assembled position when an eccentric groove 78 effects the proper movement of these two members to their assembled position. There- 45 after a dwell at 79 delays further movement of these parts while the main or central core member 67 is moved down and this is accomplished by the cam shown in Fig. 3, wherein the body portion 80 is provided 50 with a long dwell 81 and an eccentric groove 82. With the proper grooves and settings of these cams any desired progressive movement may be provided for the several parts of the core.

55 The shaft 75 may be actuated by any suitable means but it is here shown as operated by beveled pinions 83, 83^a and a hand wheel 84. The shaft 75 may be provided with a suitable indicator 85 for showing the number of operations of the machine.

60 The entire core is heated when elevated, as shown in Fig. 1, by a suitable torch 86 and is cooled as desired by any suitable means such as a pan or receptacle 87 swing- 65 ingly mounted upon suitable links 88 secured

at 89 in the frame 55. This pan normally hangs to the rear out of the way of the parts, as shown in Fig. 2, but may be readily swung to the dotted line position where the core parts in upper assembly are emersed in water 70 or other cooling medium in the pan 87.

The main mold parts are heated and a suitable arrangement is the provision of a torch 90 projecting its flame on the inside of the open plunger or mold base 8. The 75 half mold members are heated by torches 91 which are so located that their flames play upon the parts when withdrawn from assembled position.

Suitable thermocouples 92 may be arranged or mounted in the several parts with indicators 93 for use in maintaining the parts of the mold at the proper temperature and assisting in the most effective operation 80 of the machine. 85

In the use of the machine the operator applies the torches and brings the mold parts up to the proper temperature for ideal casting conditions. This may be done by overnight heating or by a sufficient heating just 90 prior to use. The metal is then poured in through the sprue until the cavity and the riser are both filled, the gas escaping through the minute openings 27 and through similar openings provided on the walls of 95 the main mold parts. When the cavity is filled, the upper core structure is then withdrawn, the main mold unlocked, the core rods forming the piston bearings withdrawn and the remaining mold parts withdrawn until 100 the casting is released and ready for removal. When the casting is removed, the parts are reassembled in the manner already described and the machine is ready 105 for another operation, it being obvious that the operator changes the wrist pin bearing core rods from time to time and cools the main core assembly by the use of the receptacle 87.

What I claim is:

1. In a piston casting machine, a frame, a mold having core openings therein, and a plurality of core parts operatively associated with said mold for movement in succession in said core opening.

2. In a piston casting machine, a frame, a mold having a core opening therein, and a core operatively associated with said mold for movement into said core opening and comprising a turret provided with a plurality of like core parts adapted for selective movement into said core opening.

3. In a piston casting machine, a frame, a plurality of separable mold parts each having a core opening, a movable core part 120 for each opening, a movable core part support, a plurality of core parts carried thereby, and means for moving said core parts successively into the core openings.

4. In a piston casting machine, a frame, 125

a plurality of separable mold parts each having a core opening, a movable core part for each opening, a core slide, a turret mounted upon said slide, and a plurality of like core parts carried by said turret and adapted to be brought selectively into mold opening position and into said core openings.

5. In a piston casting machine, a frame, a movable base member, a plurality of separable mold parts above said base member, and means for moving all of said parts into a complete cavity forming assembly.

6. In a piston casting machine, a frame, a bottom cavity forming member, separable side cavity members slidably in said frame and having core openings, core parts slidably mounted in the frame, and an operating mechanism interconnected with all of said parts for moving said side members, said base member and said core parts into a complete cored cavity forming assembly.

7. In a piston molding machine, a frame, a cavity mold carried thereby and having a core opening, a multiple piece core, and means interconnecting said parts for progressively moving the pieces of said core into complete cored assembly within said mold.

8. In a piston casting machine, a frame, a cavity mold having a core opening, a multiple part core, and means interconnecting said parts for supporting and successively assembling the pieces of said core in said mold.

9. In a piston casting machine, a frame, a cavity mold having a core opening, a multiple piece core, and means interconnecting said parts for supporting and successively assembling the pieces of said core in said mold and successively removing the core pieces from said mold.

10. In a piston casting machine, a frame, a cavity mold having a core opening, a multiple part core, and means for supporting and successively assembling the parts of

said core in said mold and comprising an operating member and timed actuating devices between it and the several core parts.

11. In a piston casting machine, a frame, a cavity mold having a core opening, a core supporting and operating device carried by said frame, and a core carried by said device and adapted to be assemble in the mold through the core opening.

12. In a piston casting machine, a frame, a cavity mold having a core opening, multiple core supporting operating devices, and movable core parts carried by said devices.

13. In a piston casting machine, a frame, a cavity mold having a core opening, multiple core supporting operating devices, and swinging core parts carried by said devices.

14. In a piston casting machine, a frame, a cavity mold having a core opening, multiple core supporting operating devices, core parts fixedly mounted on some of said devices, and movable core devices movable on other of said devices for facilitating assembly in the mold.

15. In a piston casting machine, a frame, a cavity mold thereon having a core opening, a core suitably supported in the frame and movable into said cavity, and means for varying the temperature of the core.

16. In a piston casting machine, a frame, a cavity mold thereon having a core opening, a core suitably supported in the frame and movable into said cavity, and means for cooling the core.

17. In a piston casting machine, a frame, a cavity mold thereon having a core opening, a core suitably supported in the frame and movable into said cavity, and means carried by the frame for cooling said core and comprising a movable receptacle supported by the frame and adapted to be moved into emersing position with respect to the core.

In testimony whereof I hereby affix my signature.

FRANK L. FELTES.
